UNITED STATES PATENT OFFICE

COURTLANDT B. GRIFFIN, OF LONGMEADOW, MASSACHUSETTS, ASSIGNOR TO CAREW MANUFACTURING COMPANY, OF SOUTH HADLEY FALLS, MASSACHUSETTS, A CORPORATION OF MASSACHUSETTS

PAPER MAKING

Application filed July 7, 1930. Serial No. 466,152.

This invention relates to improvements in the paper-making art and is directed more particularly to improvements in the method of and apparatus for drying a wet web of paper as it comes from the web forming apparatus.

It is common practice in paper manufacture to dry a paper web by leading it over a multiplicity of heated rigid drying drums 10 or rolls, the web being held in contact with the drums by endless aprons or felts. This method has objections because the web so held against the drums is not allowed to contract as it should when drying so that in effect it is stretched or strained or at least subjected to considerable tension. For this reason, therefore, the strength of the finished paper is impaired.

Another objection to the method outlined 20 is that the drums are necessarily heated to an extremely high temperature so that they tend to overheat the paper. In fact the temperature in some cases is so great in order to bring about the drying that there is a 25 tendency towards burning the paper, at least the extreme heat tends to bring about disintegration whereby the quality of the paper is unfavorably affected. These hot rolls act like a hot flat iron applied to a wet fabric 30 in that the paper is dried by vaporizing the moisture therein.

According to this invention there is provided a novel method of and apparatus for drying a wet web of paper wherein the web 35 is supported by non-rigid elements for the drying operation and in such a way that it is not subjected to tension or strained in any way. In fact the web may move freely relative to the supporting elements during the 40 drying whereby it may contract without strain. As a special feature by providing non-rigid supporting elements they may be adapted to absorb moisture and by being heated moisture may be driven therefrom so 45 that as distinguished from the prior art method the web being dried is neither contracted with hot rigid surfaces nor has heat applied directly thereto. This facilitates the producing of paper which has no inherent 50 strains so that it is of greater strength than

that made by present day methods while at the same time the drying is uniform so that the web has uniform characteristics.

The numerous novel features of the invention are accomplished according to the novel 50 method and apparatus to be hereinafter more fully described in connection with the accompanying drawing, wherein:

Fig. 1 is a sectional view of an apparatus of novel form adapted for carrying out the 55 novel method of the invention, and

Fig. 2 is a diagrammatic view of certain details of the apparatus.

In the drawing 2 represents a plurality of rotatable hollow drums which are heated in 60 some well-known manner. 4 and 6 represent upper and lower belts of fabric and may for convenience be called felts. These are endless and run over rolls 8 and 10. The felts are arranged to receive therebetween a 70 wet web of paper W as it comes from a paper-making machine and convey it around and between the heated drums. Preferably the paper web does not contact with the drums, but is carried between the felts so that it is 75 relieved of strains. There may be a plurality of drums which will be heated, but they will not be heated to a drying temperature for a drying function, but rather to a lower temperature for heating the felts and thereby 80 heating the web.

In the manufacture of paper a suitable size such as resin is usually added to the paper-making material or "stuff", while in the beaters. This size is not readily soluble in 85 the paper-making material whereby as the web leaves the web-forming apparatus the size may be said to be crystallized and attached to the fibers instead of being disposed uniformly throughout the body of the web. 90

It is desired according to this invention to heat the web by the means described sufficiently to cause the resin to flow or flux so that it will become more or less uniformly distributed or dispersed throughout the body 95 of the web. By running the web over the heated rolls 2 between the belts it is heated sufficiently to cause the resin to flow, rather than for any drying function, whereby the resin will be dispersed throughout the body 100

of the web. This step of the method may be called a web-heating step.

Endless belts of fabric such as 12 and 14 are provided which are supported on and driven by rolls 16 and 18. The rolls are arranged so that the belts have portions which are closely adjacent one another or are superposed on one another at places indicated at 20. These superposed portions 20 may be 10 called runs. The web leaves the felts 4 and 6 and is received between the belts 12 and 14, whereby it is carried back and forth and finally discharged in a substantially dry condition as will presently appear. The belts 15 12 and 14 are preferably of fabric adapted to absorb moisture and may be of some form of felt. For convenience they will be referred to as felts.

The rolls for supporting the felts are so 20 arranged that the runs 20 thereof are non-parallel, that is, they are preferably disposed in an angular relation to provide converging passageways therebetween while adjacent passageways converge in opposite 25 directions as shown.

In the outer and larger ends of the passageways there are located heating units indicated by 30 and air propellers in the form of electric fans 32. The units 30 are preferably 30 in the form of resistance coils or the like while the fans are arranged to direct air over the coils. In this way warmed air is delivered inwardly towards the smaller or inner ends of the passageways. To facilitate 35 the desired flow of warmed air through the passageways and to withdraw moist air there is provided at the smaller ends thereof exhaust or intake conduits 36 which are connected by piping 38 to air exhausting or suction apparatus such as an exhaust fan indicated at 40.

It will be desirable to heat the coils 30 at different temperatures. For instance, the coil of a lower run may be heated to a lower 45 temperature than a coil of an upper run. This may be accomplished by providing resistance current control device 31 in the circuits supplying the different coils as is represented in Fig. 2.

50 By means of the apparatus described heated air is blown onto the felts while at the same time moist air is withdrawn from the passageways between the felts. This is desirable for the drying operation.

55 According to the novel method the felts absorb moisture from the web and are heated as described so that they will throw off moisture and thereby function efficiently for the drying operation. In order that compara-

60 tively dry and warm felts will be provided for receiving the paper web, heating coils such as 42 are provided past which the felts travel. These serve to dry and warm the felts so that they will be in suitable condition 65 for receiving the web. Of course there may

be any desired number and arrangement of such coils.

A plurality of rolls 44 as shown for supporting the felts may be provided below the runs thereof. In this way the felts need not be under too great a tension whereby the web will be loosely embraced by the felts so that it may move and contract relative thereto. These rolls may be arranged in various ways to accomplish the purpose intended. 75

As will be observed the warm air for drying the felts is not delivered directly on to the web of paper, but rather on to the felts. In this way the felts are heated to dissipate moisture which is absorbed from the web. 80 In fact the felts are heated so that they function as moisture absorbing and web drying elements. As distinguished from rigid metal drying drums the felts are yieldable and support and overlie the web so that it may move 85 relative thereto during the drying operation. In that way the web is not strained as it is dried and the final product is uniform in its important characteristics, especially its strength. 90

It is desirable to enclose the apparatus within a room or enclosure so that the drying air is directed onto the felts and so that moist air is properly expelled. In this way proper circulation of drying air is obtained. Such 95 an enclosure is represented by walls 46. According to the invention the apparatus will be arranged so that the suction apparatus will tend to create a partial vacuum in the enclosure which will facilitate the drying operation. 100

It is desirable in connection with some types of paper to subject the web to one or more surface conditioning steps. That is, for instance, to a smoothing step whereby the 105 surfaces of the web are smoothed out. This may be accomplished by separating the felts 12 and 14 by means of supporting rolls 40 so that coacting surfacing rolls 41 may be located therebetween for receiving and acting on the web. In operation the web leaves the felts, passes between the surfacing rolls and then re-enters the felts. In this way the web is pressed so as to have certain desired surface characteristics. 115

As the web leaves the upper run of the felts it may in the well-known manner be led through apparatus for applying size thereto after which the size may be dried. Preferably in the size drying operation the web will be supported by a pair of felts after the manner described so that its strength as in the drying operation described will not be impaired by the drying operation. 120

If desired, the web may, as it leaves the drying apparatus, be run over drying drums. Since the web is now sufficiently dried, it will be free of strains and heated drums will not tend to produce strains. Or if desired from the felts the web may be passed through a 125 130

calendering machine and subsequently sized and dried. It may be subjected to various operations inasmuch as it has been properly dried.

Having described the novel method and mode of operation of the invention in the form at present preferred, what I desire to claim and secure by Letters Patent of the United States is:

- 10 1. An apparatus for continuously drying a web of paper comprising in combination, rolls spaced apart one above the other to form separate groups, which groups are spaced from one another, endless felts having superposed portions extending back and forth between the rolls of said groups to form runs extending from one group to the other, the groups of rolls being arranged so that adjacent runs are in non-parallel 15 relation forming converging passageways therebetween, means at the entrances to said passageways for directing warm air thereinto and means at the opposite ends of said passageway for withdrawing air therefrom, 20 a plurality of rolls beneath said runs serving as the sole support therefor between the rolls of said groups.

- 25 2. An apparatus for continuously drying a web of paper comprising in combination, rolls spaced apart one above the other to form separate groups, which groups are spaced from one another, endless felts having superposed portions extending back and forth between the rolls of said groups to 30 form runs extending from one group to the other, the groups of rolls being arranged so that adjacent runs are in non-parallel relation forming converging passageways therebetween, means at the entrances to said pas- 35 sageways for directing warm air thereinto and means at the opposite ends of said passageway for withdrawing air therefrom, a plurality of rolls beneath said runs serving as the sole support therefor between the rolls 40 of said groups and guide rolls associated with one of said runs acting on the felts intermediate the ends of said runs for separating the felts from one another and carrying them around a pair of paper-receiving rolls dis- 45 posed between the felts and back again into superposed relation.

- 50 3. An apparatus for drying paper comprising in combination, sets of rolls for endless felts, certain of the rolls of each set being spaced one above the other to form separate groups which are spaced from one another, portions of said endless felts supported on rolls of said groups so that they have superposed portions arranged in separated 55 runs extending between the groups of rolls and forming passageways therebetween, other non-superposed portions of said felts being supported by other rolls of said sets and means for drying said felts disposed ad- 60 jacent said other non-superposed portions, 65

guide rolls for the felts of one of said runs to separate the felts from one another and carry them around a pair of paper-receiving rolls disposed between the felts and into superposed relation again.

70 4. An apparatus for drying paper comprising in combination, sets of rolls for endless felts, certain of the rolls of each set being spaced one above the other to form separate groups which are spaced from one another, 75 portions of said endless felts supported on rolls of said groups so that they have superposed portions arranged in separated runs extending between the groups of rolls and forming passageways therebetween, other non-superposed portions of said felts being supported by other rolls of said sets and means for drying said felts disposed adjacent said other non-superposed portions, 80 guide rolls for the felts of one of said runs to separate the felts from one another and carry them around a pair of paper-receiving rolls disposed between the felts and into superposed relation again, and spaced supporting rolls beneath the said runs serving as the 85 sole support for the felts forming the said runs between the rolls of the said groups.

In testimony whereof I affix my signature.
